UNITED STATES PATENT OFFICE.

FRANK C. WHITE, OF MERIDEN, CONNECTICUT, ASSIGNOR TO THE WILCOX & WHITE COMPANY, OF MERIDEN, CONNECTICUT, A CORPORATION OF CONNECTICUT.

REGULATOR FOR A PNEUMATIC CIRCUIT.

1,082,666.

Specification of Letters Patent. Patented Dec. 30, 1913.

Application filed June 6, 1912, Serial No. 701,967. Renewed September 30, 1913. Serial No. 792,689.

To all whom it may concern:

Be it known that I, FRANK C. WHITE, a citizen of the United States, residing at Meriden, New Haven county, State of Connecticut, have invented certain new and useful Improvements in Regulators for a Pneumatic Circuit, of which the following is a full, clear, and exact description.

My invention relates to an improved governor and regulator which is of particular utility in connection with pneumatic circuits such as employed in piano player mechanism wherein it is desired to control the air tension both automatically and manually.

The present invention is essentially an improvement on the regulator and governor set forth in my co-pending application serially numbered 683,941. In the present case, the main features of construction correspond in arrangement and operation. Certain features, however, are improved so as to secure improved results.

In the accompanying drawing, the single figure is a diagrammatic illustration of such parts of a pneumatic system as are essential to a full understanding of the improvements set forth herein, the regulator being shown mainly in section.

As to the details of construction of the present case which correspond to those set forth in my companion application above referred to, it is unnecessary for me to describe the same at length since reference may be had to that case. I shall, therefore, herein only briefly describe such features.

A conventionally represents an action chest which may contain the usual striking pneumatics (not shown).

B conventionally represents an exhaustor of any suitable form for drawing air from the action chest.

C—C' represent two sections of a wind trunk leading from the action chest to the exhaustor. Between the two sections C—C' is located the regulator and governor.

D is a chest having a chamber therein.

E is a collapsible bellows. F is the movable backboard thereof.

G is a tension spring operating to move the backboard in a direction to distend the bellows.

H is what I may term a valve chest which is divided into a plurality of valve chambers, in this instance four. The wind trunk section C leads from the action chest into

the bellows E, while the wind trunk section C' leads from the chest D to the exhaustor B.

I—I'—I''—I''' are valves which respectively control ports leading from the space within the bellows to the several chambers in the valve chest H. The valves I—I'—I''—I''' are suitably connected with the movable backboard F so that as the backboard moves, these valves will be moved so as to progressively and successively open and close the series of ports controlled thereby. These connections may comprise pieces of catgut, or other suitable cord, indicated at K—K'—K''—K''' respectively. For the purpose of regulation, these connections may pass airtight through small passages in the backboard and be respectively connected with capstan screws L—L'—L''—L''' so that each valve may be independently adjusted by turning its respective screw.

M—M—M''—M''' are passages which respectively connect the interior of the chest D with those sections of the valve chest controlled by the aforesaid valves I—I'—I''—I'''. The passages M—M—M''' are controlled by normally closed cut-off valves N—N—N''' respectively. These last mentioned valves may be respectively controlled by pouch pneumatics O—O''—O'''. Air ducts P—P—P''' may connect said pouch pneumatics with a tracker board Q which may be provided with suitable note openings R and with extra openings S—S—S''' for the ducts P—P—P''' respectively, whereby when one or more of these last mentioned tracker openings is uncovered during the playing of the instrument, the pouch pneumatic or pneumatics controlled thereby will be operated to open one or more of the cut-off valves aforesaid.

T represents a by-pass which directly connects the chamber in the chest D with the space within the bellows E. This passage is normally closed by a cut-off valve U, which in turn may be controlled by a pouch pneumatic V, in turn connected by a duct W with a tracker opening X. All the cut-off valves normally stand closed. It will be observed there is no cut-off valve provided for the passage which is controlled by the regulator valve I, the reason for which will later become apparent.

J—J'—J''—J''' are springs. Each of these springs is connected at one end with one of the valves I—I'—I''—I''', while the

other end is connected with the movable backboard F of the bellows E. The tendency of the springs J—J'—J''—J''' is to close the aforesaid valves. It is at this point that the present invention discloses substantial improvement over the construction disclosed in my former application. In that case, these valve closing springs were connected at one end to the aforesaid valves and were connected at the other end to a stationary abutment independent of the backboard F of the bellows. In that case, as the backboard moved back to distend the bellows, the tension of these valve closing springs had to be overcome in opening the valves, and in that case also, the spring employed for moving the backboard had to be heavy enough to properly resist the air tension within the bellows B and the added tension of the valve closing springs J. In the present case, the springs J—J'—J''—J''' operate on the backboard F in the same direction as the bellows opening spring G, instead of against said spring G. In other words, assuming the valve I is fully closed, if the backboard F continues to move toward the valve, it will actually compress said spring, which adds that much to the resistance of spring G. The same is true of the balance of the valve closing springs. I have found that by this arrangement superior results are secured and all tendency to drag is eliminated.

Operation: It will be seen that when the apparatus is in operation, the air circuit will be through the part A, through the trunk section C, through the regulator and governor and valved passages, through the trunk section C' and through the exhauster B. When the parts stand as shown in the drawing, air will pass solely through the port controlled by the valve I, the bellows E serving to regulate the position of said valve I under varying pumping pressures so as to maintain a substantially uniform tension within the trunk C and part A. If higher tension is desired in the trunk C, the tracker opening S' is opened, thus opening the valve M', whereupon the higher tension of the exhauster B collapses the bellows E slightly more than in the first instance, and so as to close the port controlled by the valve I; whereupon the air tension will be regulated by the valve I', and so on. At any time the full tension of the exhauster B may be put in direct communication with the section C of the wind trunk by simply opening valve U, which is accomplished by uncovering the tracker opening X. By the employment of the regulator and governor herein described, any desired degree of tension may be obtained in the chest A, and the particular air tension which obtains at any time will be maintained against abnormal or noticeable fluctuation by the

automatic action of the regulator bellows E operating upon that particular valve which is in operation at that time. In effect it will be seen that the regulator operates upon an air circuit and includes at least two valve controlled passages connecting the two ends of the circuit, with a regulator valve for each of said passages, and with means for controlling one of said passages at least so that it may normally be entirely closed. In respect to operation, the present apparatus corresponds substantially to the operation of the apparatus set forth in my companion application, with the exception mentioned in regard to the action of the valve closing springs J—J'—J''—J''', the arrangement and function of which in the present case constitutes a distinct improvement over the construction disclosed in my companion case.

The operation of the cut-off valves may be controlled either manually by the tips of the fingers which may be employed as valves for tracker openings leading to the respective cut-off valve pouch pneumatics, or a note sheet may be employed as the valve, said note sheet being properly perforated to uncover such openings whenever it is desired to increase the tension above the lowest regulated tension which is accomplished through the medium of the valve I. It is obvious that the particular form of valves and pneumatics is not material.

Each spring J—J'—J''—J''' operates in effect as a yielding link between the backboard F of the bellows and each of the regulator valves respectively so that as the backboard fluctuates and moves any one of the valves I—I'—I'' or I''', the particular spring or yielding link associated with the particular valve operating at any given time offers no added resistance to the backboard. For example, as shown in the drawing, the parts are in the position which they would assume when the lowest regulated tension is obtained, such tension being controlled by the valve I. Obviously as the backboard fluctuates, the spring J and valve I move freely therewith, the tension of air within the bellows overcoming the resistance of the spring G alone. If the bellows is sufficiently collapsed so that the tension is being regulated by the valve I''', the resistance of the spring G is augmented by the springs J—J'—J'' so that the instant it is desired to return to a lower tension, the springs J—J'—J'' coöperate with the spring G in expanding the bellows to that degree necessary to bring the proper regulator valve into operation. These springs, therefore, act as assisters for the spring G under such conditions. From this, it will be seen that any tendency to drag or any sluggish movement of the bellows in returning to a lower tension from a higher tension is prevented.

What I claim is:

1. A regulator for a pneumatic circuit having two passages connecting the opposite ends of said circuit, means for causing air to flow through said passages in one direction, regulator valve mechanism coacting with at least two of said passages, means for controlling the operation thereof comprising a bellows having a movable back, means normally operating to move said back in a direction to distend said bellows, and an assister therefor, cooperating directly with said bellows and said valve mechanism.
2. A regulator for a pneumatic circuit having two passages connecting the opposite ends of said circuit, means for causing air to flow through said passages in one direction, regulator valve mechanism coacting with at least two of said passages, means for controlling the operation thereof comprising a bellows having a movable back, means normally operating to move said back in a direction to distend said bellows, and assisters therefor, said assisters operating progressively and successively.
3. A regulator for a pneumatic circuit having two passages connecting the opposite ends of said circuit, means for causing air to flow through said passages in one direction, regulator valve mechanism coacting with at least two of said passages, means for controlling the operation thereof comprising a bellows having a movable back, means normally operating to move said back in a direction to distend said bellows, and assisters therefor, said assisters comprising yielding links operatively connecting said movable back with said regulator valve mechanism.
4. A regulator for a pneumatic circuit having two passages connecting the opposite ends of said circuit, means for causing air to flow through said passages in one direction, regulator valve mechanism coacting with at least two of said passages, means for controlling the operation thereof comprising a bellows having a movable back, means normally operating to move said back in a direction to distend said bellows, and assisters therefor, said assisters operating progressively and successively.
5. A regulator for a pneumatic circuit having two passages connecting the opposite ends of said circuit, means for causing air to flow through said passages in one direction, regulator valve mechanism coacting with at least two of said passages, means for controlling the operation thereof comprising a bellows having a movable back, means normally operating to move said back in a direction to distend said bellows, an assister for said means arranged within said bellows comprising a spring operating with said bellows and said valve mechanism, and a normally closed cut-off valve for one of the passages controlled by said regulator valve mechanism.
